WILLIAM J. GILBERT, OF CINCINNATI, OHIO, ASSIGNOR TO THE COMPRESSED WOOD PRESERVING COMPANY, OF CINCINNATI, OHIO, A CORPORATION OF OHIO.

WOOD PAVING-BLOCK.

1,184,945.

Specification of Letters Patent. Patented May 30, 1916.

Application filed February 14, 1916. Serial No. 78,155.

To all whom it may concern:

Be it known that I, WILLIAM J. GILBERT, a citizen of the United States of America, and resident of Cincinnati, in the county of 5 Hamilton and State of Ohio, have invented a new and useful Improvement in Wood Paving-Blocks, of which the following is a specification.

This invention relates to improvements in 10 paving materials and particularly to improvements in wood blocks for wood block paving.

In ordinary wood block paving the blocks are laid in separated positions with relation 15 to adjacent blocks. The laying of the blocks has to be done carefully in order to provide spaces between them for the reception of sand or other agents which hold them in their separated positions. The laying of 20 the blocks in their separated positions is done to permit them to expand and contract under changes in weather conditions.

Various means have been employed for so spacing the blocks, one of which consists in 25 placing thin strips of wood between adjacent rows of blocks in order to space them, and then removing the strips as the pavement is laid. Another expedient has been to form lugs on the blocks in such a manner that 30 they extend in the directions of the grain, or in other words from the top to the bottom of the blocks which are laid in the usual manner with the end of the grain uppermost to present a wearing surface for 35 the pavement. In the last mentioned construction the lugs extending along the grain contribute largely to the splitting of the blocks because of the fact that they form fulcrum points upon which opposite ends 40 of the block may rock when it has a tendency to bend. This results in eventual deterioration of the pavement through gradual disintegration and displacement of the blocks. In addition to this objection, the 45 formation of lugs which extend in the direction of the grain permits of their being easily chipped from the block, as might occur in shipping or in loading and unloading the blocks. A further disadvantage is found

in the fact that it is frequently desirable to 50 split the block either transversely or longitudinally in order to fill in small spaces left at the edges of the pavement, and yet maintain the blocks in spaced relation by having a portion of the lug on each split portion of 55 the block. In attempting to split blocks having lugs extending longitudinally of the grain as in the ordinary construction, the lug will be left on one or the other of the split portions, it being very difficult to split 60 the lug so that each portion is provided with a lug.

It is to overcome these objections to wood block construction heretofore employed, that I have devised my improved wood block 65 construction herein illustrated and described in which an object is to provide an improved wood block having lugs formed thereon and extending substantially transversely of the grain. 70

A further object is to produce a wood block in which the lugs are so formed that splitting of an entire lug from the block is avoided in the shipping and handling of the blocks. 75

A further object is to provide a wood block in which a series of lugs are so formed thereon that the block may be readily split either longitudinally or transversely in a manner such that each portion of the block 80 is provided with a portion of the lug.

These and other objects are attained in the wood block described in the following specification and illustrated in the accompanying drawings in which: 85

Figure 1 is a fragmental perspective view of a wood block pavement built of blocks embodying my invention. Fig. 2 is a plan view of one of the blocks embodying my invention. Fig. 3 is a transverse sectional 90 view taken on the line 3—3 of Fig. 2.

The wood block embodying my invention consists of a body portion 4 having a multiplicity of series of lugs 5, 6 and 7 formed upon one side thereof, the lugs of each series being alined with the grain. The top lugs of each series are alined with one another with their longitudinal dimensions 95

extending transversely of the grain, the bottom lugs of the series being located in the same general positions on the body of the block, when considered with relation to one another. This creates lugs on the sides of the body portion, which have their grain extending transversely. At the end of the body of the block a series of lugs 8 are formed, the lugs being located one above the other, their longitudinal dimension extending transversely of the grain of the wood the same as the grain in the series of lugs 5, 6 and 7. I preferably form the end lugs in alinement with the lugs of the series 5, 6 and 7 as shown in Fig. 1. The opposite end and opposite side from the end and side having the lugs formed thereon, are left plain so that the lugs of adjacent blocks will engage therewith and maintain the blocks 10 at a sufficient distance from one another and permit of the placing of sand and pitch between them as is usual in wood block pavement construction. Although I have illustrated the construction as having the lugs in 15 absolute transverse and longitudinal alinement with each other on the blocks, I may also form them in such positions that they are in approximate alinement with one another both transversely and longitudinally 20 of the block, since the essential feature is to so construct them that their longitudinal dimensions will be in a direction substantially transverse to the direction of the grain. This permits of the location of the lugs at 25 either parallel positions with one another as shown in the drawings, or at slightly inclined or staggered positions.

By means of the construction above described it will be seen that I have provided 30 a wood block particularly adapted for paving purposes in that the lugs which hold adjacent blocks apart are so located that the block is supported against the face of an adjacent block at a number of different 35 points and at points which present sufficient bearing surface upon the adjacent block to prevent the blocks splitting as in the ordinary wood block construction having the lug extending with the grain as previously 40 described. In addition to this the lugs are so formed and located that they may press into the surface of the material of the adjacent block without the blocks having a tendency to turn or tilt when the blocks swell 45 or expand due to the absorption of water and to temperature changes. Furthermore because of the location of lugs at frequent intervals on the block's surface and in a direction transversely of the grain thereof, 50 the spaces between adjacent blocks are maintained at uniform distances without danger of being closed by warpage of the blocks. This permanently affords spaces in which the shoes of horses may secure a grip in or-

der to prevent their slipping, which slipping has previously been one of the objections had to wood block pavements. 65

One of the principal advantages attained by the transverse alinement of the lugs with relation to the grain is that portions of 70 the lug may become chipped and otherwise broken from the block without endangering the entire detachment of the lug therefrom as has been the objection to wood blocks having lugs extending with the grain. Even 75 should one lug become entirely broken off, its alined lug will act in its stead and serve to maintain the block positively in an affixed position with relation to its adjacent blocks.

An important advantage attained by my 80 improved wood block is that I am enabled to split the block either transversely or longitudinally at central points thereof and yet have block sections in which portions of the original lug remain, thus giving each section 85 the advantage of the lugs formed on the original block.

Having thus described my invention, what I claim is:

1. A wood paving block consisting of a 90 body portion having a top and bottom presenting end grain surfaces and sides and ends presenting surfaces extending with the grain, and elongated lugs formed on the sides and ends with their longer dimensions 95 extending transversely of the grain.

2. A wood block comprising a body portion having a top and bottom presenting end grain surfaces and sides and ends presenting surfaces extending with the grain, and elongated lugs formed on the sides and ends and having their longer dimensions in alinement 100 with one another and extending transversely of the grain.

3. A wood block consisting of a body portion having a top and bottom presenting end grain surfaces and sides and ends presenting surfaces extending with the grain, and a series of elongated lugs alined with the grain and having their longer dimensions 105 extending transversely of the grain.

4. A wood paving block consisting of a body portion having a top and bottom presenting end grain surfaces and sides and ends presenting surfaces extending with the grain, and elongated lugs formed on the sides and ends of the block, their longer dimensions 115 extending transversely of the grain, certain of said lugs being located intermediate of the side and end surfaces of 120 the block.

5. A wood paving block comprising a body portion having a top and bottom presenting end grain surfaces and sides and ends presenting surfaces extending with the grain, and a multiplicity of series of elongated lugs formed on the sides and ends with their longer dimensions 125 extending

transversely of the grain, the lugs of each series being alined with the grain and the longer dimensions of corresponding lugs of adjacent series being in alinement with one another and extending transversely of the grain, certain of said series being located at intermediate points of the sides and ends.

In testimony whereof, I have hereunto subscribed my name this 10th day of February, 1916.

WILLIAM J. GILBERT.
